STORM SASH

George J. Shink, Detroit, Mich., assignor of one-half to W. H. Bogart, East Detroit, Mich.

Application May 6, 1950, Serial No. 160,477

6 Claims. (Cl. 20—55)

1

This invention relates to a window panel construction and, more particularly, to a wood storm sash for a glazed metal sash.

It is an object of this invention to produce a storm sash of economical construction and which, at the same time, provides a very effective as well as attractive insulating means for a metal sash. More specifically, the invention contemplates a storm sash in the form of a wood frame adapted to be attached to a metal sash and an insert panel provided with glazing adapted to be removably inserted within the frame. In order to reduce as much as possible the cost of mill-work on the frame, as well as the frame members of the insert panel, the sash of this invention is preferably designed so that each of the frame members for the insert panel are of the same shape and size in cross section. Likewise, each of the side members of the frames are of corresponding cross section, and the top and bottom frame members preferably have the same cross section.

In the drawings:

Fig. 1 is a front elevation of the sash of this invention mounted on a glazed metal sash.

Fig. 2 is a sectional view taken along lines 2—2 in Fig. 1.

Fig. 3 is a sectional view taken along the lines 3—3 in Fig. 1.

Fig. 4 is a perspective view of the storm sash with the insert panel partially removed.

Fig. 5 is a view corresponding to Fig. 2 illustrating the manner in which the insert panel is manipulated for removal from the outer frame.

Fig. 6 is an enlarged fragmentary sectional view showing the insert panel seated in its operative position.

Referring to the drawings, and particularly to Fig. 4, there is illustrated a metal sash 10 of conventional design which comprises a casing 12 at one side of which there is hinged, as by hinges 14, a metal framed window 16. Casing 12 is provided with a conventional locking handle 18 and a handle 20 for opening and closing the window 16.

The storm sash of this invention includes an outer wood frame 22 which is constructed of a pair of upright stiles 24 and a pair of top and bottom rails 26. Stiles 24 are milled sections provided with a longitudinal stop member 28 on the face thereof which defines the inner periphery of frame 22. Top and bottom rails 26 are likewise formed as similarly milled sections. Each of the rails 26 are fashioned on the face thereof which defines the inner periphery of

2

frame 22 with a groove 30 and a stop member 32 extending along the inner side of groove 30. Stiles 24 and rails 26 are preferably of the same size in cross section, stiles 24 differing from rails 26 only in the provision of groove 30. In other words, stiles 24 can be fashioned into rails 26 by simply milling therein groove 30. In other respects, the stiles and rails may be of identical shape and size in cross section.

Outer frame 22 is of a size corresponding to metal sash 16 and is adapted to be fastened against the outer face of sash 16 by mounting screws 34.

Within frame 22 an insert panel 36 is arranged to be removably secured. Panel 36 is formed with top and bottom frame members 38 and side frame members 40 which are secured together at their corners to form a substantially rectangular wood frame provided with a glazing 41. Frame members 38 and 40 are milled with cross sections of identical shape and size, these members being different only with respect to their length. Frame members 38 and 40 are milled on the one face thereof which defines the outer periphery of frame 36 with a groove 42 having an outwardly extending flange 44 on the outer side thereof and a tongue 46 on the inner side thereof. The edge contour of members 38 and 40 is to some extent complementary to the edge contour of top and bottom rails 26 of the outer frame 22. Or stated differently, when the insert panel 36 is fitted within outer frame 22, tongue 46 is arranged to interfit with groove 30 and tongue 48 adjacent the outer face of frame 22 is arranged to interfit with groove 42. At the same time, flange 44 overlaps and abuts against the outer face of rails 26 and the inner face of panel 36 abuts against stop members 32.

In order to permit inserting panel 36 within the opening defined by frame 22, the panel is somewhat shorter in height than the effective height of the opening of frame 22. The difference in these heights is illustrated clearly in Fig. 5, where it will be noted that the vertical distance 45 between the ends of tongues 46 is slightly less than the vertical distance between the bottom of groove 30 at the upper end of frame 22 and the top face of tongue 48 along the lower end of frame 22. The distance between the ends of tongues 46 is however greater than the vertical distance between the ends of tongues 48 so that, 50 in order to insert panel 36 within the opening of frame 22, it is necessary to hold the panel in a position inclined forwardly at its upper end to the plane of frame 22, Fig. 4, and then push the

panel upwardly to interengage groove 42 with tongue 48 at the upper end of frame 22.

Within groove 30 on lower rail 26 there are arranged several screws 50. These screws can be threaded into the wood a greater or lesser extent to thereby control the effective depth of groove 30. The heads of screws 50 are always elevated from the bottom wall of the groove to an extent such that when panel 36 is dropped from the position shown in Fig. 5 to that shown in Fig. 6, tongue 46 at the upper end of the panel is still engaged at least partially within groove 30 at the upper end of the frame 22.

A pair of clips 52, each having an offset portion 54, are mounted on stiles 24 and arranged to be pivoted such that when panel 36 is arranged within the opening of frame 22 the offset portions 54 overlie the flange portions 44 and prevent movement of panel 36 in a direction outwardly of frame 22. Panel 36 is normally prevented from falling out by the interlocking tongue and groove engagement of the respective members of the frame and panel at the upper and lower ends thereof, and clips 52 are provided merely for the purpose of preventing the panel from falling out of frame 22 should it be accidentally displaced upwardly such as when the window is being washed.

As was described very briefly above when it is desired to insert panel 36 within the opening of frame 22, the panel is tilted toward the plane of frame 22 at its upper end and then pushed upwardly to engage tongue 48 at the upper end of the frame within groove 42 at the upper end of the panel. Grooves 42 and 30 are, of course, slightly wider than tongues 46 and 48, to permit such interengagement of the tongues with the grooves while panel 36 is in the inclined position. The lower end of panel 36 is then swung inwardly to a position where the inner face of lower frame member 38 abuts against the outer face of stop 32. Panel 36 is then permitted to drop so that it is supported at its lower end upon screws 50.

When panel 36 is arranged within frame 22 in the manner above described, it will be noted that the flange portion 44 on frame members 38 and 40 overlap the outer face of frame 22 around the entire frame opening. This arrangement provides not only an effective seal between panel 36 and frame 22 but also a very attractive construction. It will also be noted that the grooves 30 on the side frame members 40 do not interengage with a tongue on the stiles 24. These grooves simply provide a vertically extending channel along the vertical edges of panel 36, which channel provides a passage for rain and moisture that may accumulate between the peripheral edges of the panel and outer frame. In the absence of grooves 30 on the side members 40, the moisture accumulating between the edges of panel 36 and frame 22 would gradually seep into the space between the glazing of the metal sash 16 and the storm window. These grooves therefore have a very important function and, at the same time, enable the milling of the members 38 and 40 with the same cross section. In other words, both of these members may be cut from the same stock.

The screws 50 likewise have a dual function. They enable the milling of the top and bottom frame members 38 to the same cross section and, at the same time, they allow for adjustment of panel 36 within frame 22, which adjustment often becomes necessary because of

shrinkage, expansion, or warping of the wood.

It will thus be seen that I have provided a storm sash construction which is not only economical but also very attractive. The construction furthermore provides a very effective means for insulating a metal sash and enables the insertion and removal of the insert panel from its outer wood frame to be performed as a very simple operation.

I claim:

1. A storm sash construction comprising an outer frame having top and bottom rails and upright stiles at each side thereof, said top and bottom rails being of identical cross section and reversed in position, the faces of said top and bottom rails which define the inner periphery of said frame having a longitudinally extending groove therein spaced intermediate the inner and outer faces of said rails, the portion of said rails between said groove and the outer faces of said rails defining a tongue extending lengthwise of the rails, an inner frame having glazing thereon and adapted to fit into and close the opening defined by the inner periphery of the outer frame, said inner frame having top, bottom, and side frame members, said frame members each having a continuous flange adjacent the outer face thereof which is adapted to overlie at least a portion of the outer face of said outer frame when the inner frame is inserted within the opening of the outer frame, the inner face of said flange on the top and bottom frame members defining one side of a longitudinal groove in the face of said top and bottom frame members which define the outer periphery of said inner frame, the portion of said top and bottom frame members between said last mentioned groove and the inner face of said top and bottom frame members defining a tongue extending lengthwise of said top and bottom frame members, the tongue and groove in said top and bottom frame members being arranged to interfit, respectively, with the groove and tongue on the top and bottom rails of said outer frame when the inner frame is inserted within the opening of the outer frame, the vertical distance between the tongues on the inner frame being greater than the distance between the tongues on the outer frame and less than the distance between the bottoms of the grooves on the outer frame, and means positioned between the bottom of the groove on the bottom rail of the outer frame and the tongue on the bottom rail of the inner frame for varying the effective depth of the groove on the bottom rail of the outer frame.

2. The combination set forth in claim 1 wherein said top, bottom, and side frame members of said inner frame are identical in cross section, the groove in said side frame members forming vertical rain channels along the vertical end faces of said inner frame which are spaced intermediate the inner and outer faces of said inner and outer frames.

3. A storm sash construction comprising an outer frame having top and bottom rails and upright stiles at each side thereof, said top and bottom rails being of identical cross section and each having on the face thereof which defines the inner periphery of said frame a pair of longitudinally extending spaced apart tongues defining a longitudinally extending groove therebetween, one of said tongues being adjacent the outer face of said rails and the other tongue being spaced intermediate the inner and outer faces of said rails, said intermediate tongue being of greater

height than said other tongue, a glazed panel section adapted to be inserted within the opening defined by said outer frame and having top, bottom, and side frame members, said top and bottom frame members being identical in cross section and having on the face thereof which defines the outer periphery of said panel section a pair of longitudinally extending spaced apart tongues defining a longitudinally extending groove therebetween, one of said tongues being flush with the outer face of said frame members and the other tongue being flush with the inner face of said frame members, said outer tongue being greater in height than the inner tongue, said side frame members having on the face thereof defining the outer periphery of said panel section a tongue corresponding in size and shape with the outer tongue on said top and bottom frame members and cooperating therewith to form a peripheral flange on the outer face of said panel section which is arranged to overlap the outer face of said outer frame adjacent the inner peripheral edge thereof, said tongues and grooves on said outer frame and said panel section being arranged so that, when said panel section is inserted within the opening of the outer frame, the inner tongues on the top and bottom frame members of said panel section engage within the grooves on the top and bottom rails of said outer frame, and the outer tongues on the top and bottom rails engage within the grooves on the top and bottom frame members of said panel section, said top and bottom rails being spaced apart vertically so that, when said panel section is inclined with its upper end toward said outer frame and the inner tongue on said upper frame member is inserted within the groove in the top rail of the outer frame, the lower end of the panel section may be swung inwardly to an upright position where said peripheral flange abuts against the outer face of said frame and then permitted to shift vertically downwardly sufficiently to engage the inner tongue on the bottom frame member of said panel section within the groove on said lower rail, and means within at least one of said bottom grooves

5

for retaining the interengaged tongue in spaced relation to the bottom of said last mentioned groove to prevent disengagement of the inner tongue on the top frame member from within the groove on the top rail of said outer frame.

10

4. The combination set forth in claim 3 wherein said last mentioned means comprise vertically adjustable screws threaded into the bottom wall of the groove for varying the effective depth of said groove.

15

5. The combination set forth in claim 4 wherein in said side frame members of said panel section are identical in cross section with the top and bottom frame members of said panel section, said grooves in said side frame members providing vertical channels at the vertical joints between said outer frame and said panel section, said vertical channels being spaced intermediate the inner and outer faces of said outer frame and panel section.

20

6. The combination set forth in claim 1 wherein in said last mentioned means comprise screws threaded into one of said bottom frame members and contacting the other frame member so that the tongue of the frame member is spaced from the bottom of the groove with which the tongue interfits.
